UNITED STATES PATENT OFFICE.

WILLIAM G. LOY, OF MINNEAPOLIS, MINNESOTA.

LOCOMOTIVE-BOILER.

1,162,296.

Specification of Letters Patent. Patented Nov. 30, 1915.

Application filed November 15, 1913. Serial No. 801,311.

To all whom it may concern:

Be it known that I, WILLIAM G. LOY, a citizen of the United States, and a resident of Minneapolis, in the county of Hennepin and State of Minnesota, have invented certain new and useful Improvements in Locomotive-Boilers, of which the following is a specification.

My invention relates to certain improvements in the construction of locomotive boilers of a type having one or more partitions or so called water walls extending longitudinally across the fire box, dividing said fire box into two or more fuel spaces, from the grate up to the fire tubes in front and from the grate up to the fire door in the rear, leaving one combustion chamber and providing for the deposit of fuel through one fire door.

As is well known, boilers of the locomotive type usually employed for this purpose are of comparative low efficiency owing chiefly to the fact that they have relatively small heating surface, such surface being composed wholly of the fire box and fire tubes.

The primary object of my invention is, therefore, to provide a boiler of the locomotive type which shall have a larger heating surface and hence a higher efficiency than those heretofore employed.

A further object of the invention is to provide this increased heating surface without increasing the external dimensions or altering the standard shape of the boilers, whereby my improved boilers may be mounted on any well known form of locomotive substantially without change.

My improvement is not limited in application to any specific form of wide fire box boiler as it may be applied to the well known "Belpaire," "Wootten" or "Narrow firebox" boilers.

In the following specification and the accompanying sheet of drawings, I have shown my invention in its preferred form, but as this may vary, I claim all such changes as may come within the spirit and scope of my invention and claims.

In the drawings I have shown so much of the outline of a typical locomotive boiler in its conventional form as to enable those skilled in the art to understand and apply my invention.

In the said drawings Figure 1 represents

a longitudinal section through a portion of a locomotive boiler having water walls embodying my invention, and Fig. 2 represents a transverse section taken on line $\alpha-\alpha$ of Fig. 1. Fig. 3 is a perspective view of the water wall showing certain detail of construction hereinafter referred to.

My invention contemplates broadly the provision of one or more water walls whose surface is exposed to the hottest part of the fire, to this end I arrange the water walls near the grate now to be described.

The same reference characters represent the same parts in the different figures.

Referring to the drawings in detail, 1 represents the boiler proper, 2 and 3 are the front and rear water spaces respectively, while 4 represents the side water spaces.

5 represents the crown sheet, below said crown sheet are located my water walls extending from the grate up to the fire tubes at its front and from the grate up to the fire door in its rear. As is shown in Fig. 3 the top and bottom of the water wall 9 are closed. The front and rear ends of the water walls are flanged 13 connected to the tube sheet 6 and fire door sheet 7 by patch bolt or rivets 12.

The front end of water wall 9 is open to and communicates directly with the front water space through suitable openings in rear tube sheet 6. The rear end of the water wall is open to and communicates directly with the rear water space 3 through a suitable opening in the door sheet 7, thereby affording an effective circulation with the front and rear water spaces. The central water walls 9 are supported in the usual manner by stay bolts, 11, connecting the walls. The water wall 9 is inclined at its top from the center toward the ends to accelerate the ebullition of the steam bubbles into the boiler proper.

As regards the connection of the water walls, with the flue sheet and the inside fire door sheet, said sheets may be flanged inwardly, *i. e.*—toward the center of the fire box at their openings and the water wall securely riveted to said flange.

I do not desire to restrict myself to welding the joints as shown in Fig. 3, as in some cases I may resort to riveting.

It will be seen that I have provided a highly efficient boiler, having many points of superiority over those now in use, and it

is thought that the advantages thereof will be readily appreciated by those skilled in the art.

What I claim is:

- 5 1. The combination in a boiler type having the usual front, rear, and side water spaces forming the front, rear, and side water walls of the fire box, combustion chamber, and fire tubes, one or more water walls 10 extending longitudinally across said fire box, at its front connected with the rear flue sheet and its rear with the inside door sheet, said water walls being flanged outwardly at the ends where connected to said flue sheet and door sheet, said sheets having suitable openings to allow water to circulate through said water walls all substantially as set forth.
- 15 2. In a combination water wall and fire

tube boiler of the locomotive type, front, 20 rear, and side water spaces forming the front, rear, and side walls of the fire box, a boiler body extending forwardly from said front water space and having the usual fire tubes arranged therein, water walls extending longitudinally across the fire box connecting the front and rear water spaces extending from the grate up to the fire door in the rear and from the grate up to the fire tubes in the front, the top of said water 25 wall being inclined from the center upwardly toward the ends to accelerate the ebullition of the steam bubbles into the boiler proper substantially as described.

WILLIAM G. LOY.
